(57) **CLAIM**

The ornamental design for a food thermometer set, as shown and described.

DESCRIPTION

FIG. 1 is a front perspective view of a food thermometer set, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view thereof, shown in an alternate split configuration.

The broken lines in the drawings illustrate the portions of the food thermometer set, which form no part of the claimed design.

1 Claim, 9 Drawing Sheets
